Primary Examiner — Jennifer Rivard(74) *Attorney, Agent, or Firm* — QuickPatents, Inc.; Kevin Prince(57) **CLAIM**

I claim the ornamental design for a roll-up tote bag, as shown and described.

DESCRIPTION

FIG. 1 is a perspective view of a roll-up tote bag, illustrated in a rolled configuration, showing my new design;

FIG. 2 is a perspective view thereof, illustrated in a flat configuration;

FIG. 3 is a front elevational view thereof, illustrated in the flat configuration;

FIG. 4 is a rear elevational view thereof, illustrated in the flat configuration;

FIG. 5 is a left-side elevational view thereof, illustrated in the flat configuration;

FIG. 6 is a right-side elevational view thereof, illustrated in the flat configuration;

FIG. 7 is a top plan view thereof, illustrated in the flat configuration; and,

FIG. 8 is a bottom plan view thereof, illustrated in the flat configuration.

The broken lines showing a person in FIG. 1 are included for the purpose of illustrating the invention in use, and form no part of the claimed design.
